R. E. HUMPHREY

RADIO RECEIVING APPARATUS

Filed Nov. 5, 1924

Inventor
Reginald E. Humphrey

By *John B. Brady*
Attorney

UNITED STATES PATENT OFFICE.

REGINALD E. HUMPHREY, OF SWANTON, VERMONT.

RADIO RECEIVING APPARATUS.

Application filed November 5, 1924. Serial No. 747,931.

My invention relates broadly to a radio receiving system and more particularly to a circuit arrangement for an electron tube system at a radio receiving station wherein the functions of radio frequency amplification, rectification and audio frequency amplification may be simultaneously performed without the generation of oscillations or disturbing currents in the radio receiving system.

10 One of the objects of my invention is to provide an inexpensive form of radio receiving apparatus having a high degree of efficiency and capable of volume reception of the incoming signaling energy.

15 Another object of my invention is to provide an arrangement of electron tube and circuit therefor wherein the tube functions simultaneously as a radio frequency amplifier, a rectifier and an audio frequency amplifier.

20 Still another object of my invention is to provide a construction of electron tube including a plurality of sets of electrodes, one set of which serves for the amplification of incoming signaling energy at a plurality of 25 different frequencies, while the other set of electrodes operates to produce the said difference in frequency by a process of rectification.

25 A still further object of my invention is to provide a tube construction wherein an evacuated vessel is provided with a pair of cathodes and a pair of anodes with a control electrode interposed between one of said cathodes and anodes for controlling amplification 30 of energy at both radio and audio frequencies while the other cathode and anode are arranged for the rectification of electrical energy.

35 My invention contemplates the provision of a circuit for radio receiving systems wherein a single tube may be employed to produce a greater volume amplification of the incoming signaling energy than has heretofore been possible. It is unnecessary to employ auxiliary rectification devices with the tube of my invention by reason of the inherent rectification powers possessed by the tube in addition to its powers of amplification at different frequencies.

40 My invention will be more clearly understood by reference to the following specification and from the accompanying drawings, in which:

45 Figure 1 illustrates the application of the electron tube of my invention to a radio receiving circuit; and Fig. 2 shows in detail the

arrangement of the plurality of sets of electrodes within the evacuated vessel.

50 Heretofore in the art it has been proposed to amplify incoming signaling energy at a radio receiving station at both radio and audio frequencies. It has been necessary to utilize a plurality of three electrode tubes in order to accomplish desirable results or it has been necessary to utilize a rectifier of the 55 crystal variety in reducing the frequency of the incoming radio frequency energy to a readily amplifiable audio frequency at which the signals might be observed. The employment of this apparatus lends complications 60 in a radio receiving system which is employed as a receiver of broadcast entertainment by a novice or one unskilled in the art. The employment of a number of individual pieces in a broadcast receiver requires independent adjustment of several controls by an operator who may be unskilled in the art with the result that imperfect reception is secured. Furthermore the several pieces of apparatus 65 heretofore required have been undesirable 70 sources of expense and it is the purpose of my present invention to provide a simplified arrangement of radio broadcast receiver wherein the tube and the circuit provided for the 75 tube performs simultaneously a plurality of 80 functions without undesirable oscillation, regeneration or reradiation of the signaling 85 energy.

90 Referring more particularly to the drawings, reference character 1 designates the antenna system and 2 indicates the ground of the radio receiving circuit. A primary winding 4 is interposed in the antenna system forming a part of the coupling transformer 3. The antenna circuit is tuned by 95 variable condenser 6. Secondary winding 5 is coupled to the primary winding 4 and is tuned by secondary condenser 7. The electron tube comprises an evacuated vessel 8, Y supports 9 and 10 at one end of the tube 100 and 11 and 12 at the other end of the tube between which the filamentary cathodes 14 and 15 are supported. Connections 16 and 17 are brought out from the opposite terminals of the Y supports and taken to the cathode heating circuit. A control electrode 18 is provided adjacent the cathode 15 connected with the external circuit through conductor 19. A plate or anode electrode 20 is positioned adjacent the control electrode 18 105 and in a position to receive electronic bombardment from cathode 15. A connection 110

is brought out from anode 20 of the tube as represented at 20^a. The other anode 21 of the tube is disposed adjacent cathode 14 and is connected with the external receiving circuit through lead 21^a. Radio frequency signaling energy is impressed on the input circuit of the electron tube by connections extending from the tuned circuits 5 and 7 through the conductor 19 to control electrode 18 and from the other side of the tuned circuit through a condenser 28 and a connection back to the cathode 15. The circuit described forms the input circuit for the tube operated at radio frequency. The output circuit formed by anode 20, lead 20^a, primary winding 23 of the radio frequency transformer 22, condenser 26, high potential battery 27 and a return connection to the cathodes 14 and 15. The transformer 22 is provided with a secondary winding 24 in which amplified radio frequency energy is existent having been transferred from the primary winding 23. The secondary winding 24 is connected in circuit with primary winding 31 of audio frequency transformer 29 with a return connection to the filamentary cathode 14. The other side of the secondary winding 24 connects with anode 21 through lead 21^a completing the rectification circuit. The filamentary cathodes 14 and 15 are heated to incandescence from a source of potential 32 under control of rheostat 33. The audio frequency transformer 29 operates to transfer energy from the primary winding 31 to the secondary winding 30 at audio frequency, which energy is again impressed upon the input circuit comprising control electrode 19 and cathode 15 whereby the energy is considerably amplified.

fied and finally caused to operate responsive 40 device 25 in the output circuit of the set of electrodes comprising the amplification system of the tube.

It will be observed that the electron tube contains one set of electrodes independent 45 from another set of electrodes with circuit connections between the electrodes arranged for the amplification of the incoming signaling energy at radio frequency, next the rectification of the said energy and finally the 50 amplification of the rectified energy at audio frequency. In this manner a plurality of functions are performed by the same electron tube and the receiving system is simplified and its cost reduced so that it is readily available to the general public. 55

While I have described my invention in certain particular embodiments I desire that it be understood that modifications may be made and that I intend no limitations 60 upon the invention other than those imposed by the scope of the appended claim.

What I claim and desire to secure by Letters Patent of the United States is as follows:—

An electron tube structure comprising in combination an evacuated vessel, a pair of Y-shaped conductive members extending into said evacuated vessel with the axes thereof centered one over the other and aligned 70 with each other at opposite ends thereof, a pair of filamentary cathodes supported from the extremities of said Y-shaped conductive members, an anode mounted adjacent one of said filamentary cathodes, and a grid and 75 anode mounted adjacent the other of said filamentary cathodes.

REGINALD E. HUMPHREY.
